UNITED STATES PATENT OFFICE.

JOSEPH B. HAVRILLA, OF HOMESTEAD, PENNSYLVANIA.

RIVETING DEVICE.

Application filed February 7, 1925. Serial No. 7,662.

My invention relates to the art of riveting, being more particularly a riveting tool which is supported and magnetically held against the plate in such a manner as to take up or cushion the jar of the tool during the riveting operation. In handling riveting tools, the jar or impact of the tool is communicated directly to the operator to such an extent that such work is very fatiguing to the operator and eventually results in a disablement of the operator for such work.

The principal object of my invention is to produce a riveting device of simple form and construction, in which the riveting tool proper is mounted for rotary movement and elastically in a support, which, during the riveting operation is magnetically held against the plate upon which the work is being performed, whereby the jar or impact of the tool is absorbed and not communicated to the operator, and whereby the tool may be moved relative to the support for properly rounding the rivet head.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is a side elevational view of a riveting device constructed in accordance with the present invention,

Figure 2 is an enlarged perspective view showing a portion of the support for the riveting tool,

Figure 3 is an end view of the device shown in Figure 2,

Figure 4 is an enlarged transverse section taken upon the line 4-4 of Figure 3 with parts omitted,

Figure 5 is an enlarged sectional view taken substantially upon line 5-5 of Figure 1 with parts omitted,

Figure 6 is an enlarged perspective view of the hammer of the riveting tool with its attached ball member,

Figure 7 is a fragmentary view partly in elevation and partly in longitudinal section

showing the hammer of the riveting tool and adjacent parts, and

Figure 8 is a fragmentary view illustrating the use of a bucking tool with the riveting tool.

The riveting tool consists of a body 10, a handle 11, and a hammer 12. In the form shown, the tool is of the pneumatic type, being supplied with air under pressure through a flexible connection indicated at 13, such air pressure being controlled as is usually done by a lever indicated at 14.

The riveting tool is supported by a device which embodies a ball member 15 that is slidably keyed to the shank of the hammer 12 and is received within a socket 16 which has a substantially L-shaped supporting arm 17 formed integral with the U-shaped foot 18. By the employment of this construction, the riveting tool will be capable of a rotary movement within the socket 16 and the same may also be moved longitudinally relative to the said socket member. The foot 18 is hollowed out or recessed to form a pocket 75 to receive a winding 19 which is arranged about a core 20, the foot forming an electric magnet for the purpose hereinafter described.

The supporting arm 17 is hollow as indicated at 21, and wires 22 and 23 extend therethrough from the winding 19 said wires extending through a hollow rod or bar 24 which is attached as at 25 at its inner end to the transversely extending arm portion 26 of the arm 17 and which is rigidly connected at its outer end with a collar 26 that loosely surrounds the body 10 of the riveting tool. A switch 27 is carried by the bar or rod 24 and properly connected to the wires 22 and 23 so as to control the flow of current to the winding 19, said wires 22 and 23 being extended through the outer end of the rod 24 for connection with a suitable source of electrical supply. By reason of the loose relation between the collar 26 and the body 10, the body of the riveting tool may be allowed to move laterally in all directions to a limited extent relative to the said collar 26, but it is obvious that the same results may be obtained by flexibly connecting the ends of the rod 24 with the arm 17 and the collar 26.

lar 26. Surrounding the body 10 and having its end respectively engaging the collar 26 and a flange 28 upon the inner end of the body 10, is a coiled or helical compression spring 29. It will thus be seen that by reason of the fact that the hammer shank may slide through the ball member 15, the impact of the hammer with the rivet will be transmitted to the body 10 and the shock thereof absorbed by the spring 29.

Two plates are shown upon which the work is being performed, said plates being indicated at 30 and 31, and the rivet being indicated at 32.

15 A bucking tool is provided to be held against the plate on the opposite side of the same to the hammer 12 of the riveting tool.

In the illustration of Figure 8, the support is used for the purpose of supporting 20 the bucking tool, it being understood that the support is constructed as above described in connection with the riveting tool when used for supporting the bucking tool. When thus used, the impact ordinarily received by 25 the bucking tool is reduced and absorbed during the operation of riveting. The bucking tool is generally indicated by the reference character 33.

By forming the electromagnet 18 of U- 30 shape as shown so as to partially surround the hammer 12 and the rivet 32, only a single electromagnet structure need be provided, and the latter requires only one supporting arm 17 for connecting the same with the 35 socket member 16.

When a rivet is to be headed, the riveting tool is placed in position with the hammer 12 over the rivet and with the foot 18 resting against the plate 31 to be riveted, as 40 shown in Figure 1. The switch 27 is then closed and the foot becomes magnetized a sufficient degree to hold the support firmly against the plate during the riveting operation. The air is then admitted to the tool 45 by operation of the lever 14 and the riveting action takes place, the tool being held against the rivet by the person operating the device with the assistance of the spring 29. The shock caused by the impact of the hammer 50 12 is absorbed to a large extent by the spring 29, thereby relieving the operator from the force of the shock which is ordinarily directly received by the person holding the tool.

55 When the riveting operation has been finished, the air is shut off so that the riveting action is stopped, and the switch 27 is opened for permitting the support to be readily detached from the plate and moved into position for the next rivet.

From the foregoing description it is believed that the construction and operation as well as the advantages of the present invention will be readily understood and appreciated by those skilled in the art.

Minor changes may be made without departing from the spirit or the scope of this invention as claimed.

What I claim as new is:—

1. In an electromagnetic tool support a 70 U-shaped magnet adapted to contact with a metallic surface, an L-shaped supporting arm formed integral with the U-shaped magnet and extending rearwardly therefrom, a socket formed with the upper end 75 of the arm and disposed in horizontal alignment with the space between the two legs of the magnet, a reciprocable tool movable between the legs of the magnet, a ball member formed thereon and mounted in said socket, a bar carried by the L-shaped arm and extending parallel to the tool, and a collar formed with the outer end of the bar and supporting part of the tool.

2. A riveting device comprising a substantially L-shaped supporting member having a socket at one end, a magnetized foot carried by the opposite end thereof, a riveting tool extending through the said socket and having a ball received therein, a collar loosely arranged on the outer end of said riveting tool, connections between the collar and the said supporting member, and a coiled spring interposed between said tool and said collar. 95

3. A riveting device arranged to absorb shock comprising an L-shaped supporting member, having a socket at its upper end, a U-shaped foot carried by the opposite end of said supporting member, a coil in the foot, means for energizing said coil, a riveting tool extending freely through the said socket and pivotally secured therein, a collar loosely arranged on the outer end of said riveting tool connections between the collar and said supporting member, and a coiled spring interposed between said tool and said collar. 100

4. In combination, a riveting tool having a hammer provided with a shank formed with a ball member and a flange, a supporting member having a socket for receiving the said ball member, a foot parallel with the said socket member and carried thereby, a coil in said foot, a collar loosely surrounding the other end of the riveting tool, a hollow rod connecting the collar and the said supporting member, an expansion spring interposed between said collar and flange and surrounding the said tool, and means for energizing the coil including wires extending through said hollow rod. 110

5. In combination, a riveting tool having a hammer provided with a shank, a ball and socket joint including a ball member slidably mounted upon the hammer shank, said ball and socket joint further including a socket member engaged with the ball member, a U-shaped foot parallel with the socket member, a leg rigidly connecting the socket mem- 125 ber, 130

ber with the foot, a coil in said foot, means for energizing said coil, a collar loosely surrounding the outer end of the riveting tool and connected to the socket member, an abutment on the riveting tool, and a compression spring interposed between the abutment and said collar, the connection between the collar

and the socket member embodying a hollow rod having a switch mounted thereon, and the means for energizing the coil including 10 wires extending through said rod and connected to the switch.

In testimony whereof I affix my signature.
JOSEPH B. HAVRILLA.
